UNITED STATES PATENT OFFICE

EDMOND I. HETSCH, OF NEW YORK, N. Y.

ASHFAN AND BLOW OFF MUFFLER STRUCTURE

Application filed May 18, 1931. Serial No. 538,105.

My invention relates to railway rolling stock and consists in a novel locomotive ashpan and boiler blow off muffler structure.

The boiler blow off cock on a locomotive is usually located along the firebox mud-ring in such a position as to direct the blow off steam away from the side of the engine. Steam blown off from the boiler through this cock forms a dense cloud obstructing the vision from other vehicles operating in the vicinity and also endangering persons and property near the blow off cock from steam and hot water. Since frequent blowing off is desirable as it tends to maintain the boiler water free from scale and sludge, it is desirable to provide means whereby the blow off operation may safely take place at any time.

Blow off mufflers have been devised which comprise separate units, adapted to be mounted beneath the boiler, which direct the blow off steam onto the track under the train. This equipment, however, requires maintenance and expense to prevent loosening of the attaching means, and, where the muffler is attached to the ashpan, bolts or rivets must pass through the wall thereof. If these become loose, the enclosed body of ashes may be subjected to drafts which tend to keep the coals in a state of combustion and increase the heat and consequent warping effect upon the ashpan walls.

The main object of my present invention is to provide a blow off muffler which will occupy a minimum amount of space, will direct the steam harmlessly onto the track beneath the train, and will not be affected by vibration of the locomotive. I attain this general object and other detail objects in the structure illustrated in the accompanying drawing in which—

Figure 1 is a top view of my combined ashpan and blow off muffler structure.

Figure 2 is a side view of the same.

Figure 3 is an end view of the same.

Figure 4 is a detail view showing a modified form of outlet.

Referring to the drawing, my ashpan structure is carried by the firebox mud ring 1, or in any suitable manner, and includes an upper portion 2 having sloping side and

end walls and a lower portion 3, including a hopper which projects through the cradle (not shown) of the engine main frame and through the trailer truck frame, if present. The upper and lower portions may be formed separately and secured together by means of rivets 11.

The upper portion 2 includes wheel depressions 4 above the rear drivers 5 and aprons 6 extending outwardly from the mud-ring 1 to provide for circulation to the grates. The lower portion 3 of the ashpan has sloping front and rear walls 7 and 15 respectively, and substantially vertical side walls 9. The walls of this portion are provided with external and internal reinforcing ribs 13 and 14, respectively, to strengthen the structure and assist in withstanding the warping effect of hot ashes.

The rear wall 15 of the hopper forms an extension on the rear wall of the upper portion 2 and the outer rear wall 8 of the lower portion is offset from wall 15, and, with the side walls 9 and 10, encloses the muffler passage 23 which occupies the rear of the lower portion 3. Baffle plates 26 extend between the walls 8 and 15 and serve to break the direct passage of steam through the muffler. Openings 18 are provided in wall 8 for attachment with hose connections 19, which at their upper ends, lead from the blow off cocks 20. Rods 21, having handles 22 on their upper ends, project up through the floor of the engine cab for manual operation of the blow off valves. Passages 17 depend beneath the bottom 16 of muffler passage 23 and open rearwardly thereof so as to direct the blow off steam beneath the train. The bottoms of these outlet passages merge with the lower edge of hopper wall 15 and grooved elements 25 are provided to carry the hopper door (not shown).

Where the engine has a trailer truck which may or may not be equipped with a booster, extension pipes may be attached to the outlet passages to direct the blow off away from the booster and trailer axles. In Figure 4, outlet passages 24 are provided with bolted collars for attachment of extension pipes. In other respects, the structure on this modi-

fication is the same as that previously described.

My combined blow off muffler and ashpan device provides a compact structure in which the size of the hopper is not decreased and at the same time the exhaust device does not project unduly from the ashpan into space required for other equipment. The ash retaining walls are imperforate webs of cast metal which are well adapted to resist the warping effect of the hot ashes as well as load stresses, and any possibility of the enclosed ashes being exposed to drafts is obviated.

Obviously, my invention is not limited to the exact forms which I have illustrated and described, but various modifications as to details of structure, location of the parts, etc. may be made without departing from the spirit of the invention and I contemplate the exclusive use of all such variations which come within the scope of my claims.

I claim:—

1. As a new article of manufacture, a locomotive integral ashpan structure including a hopper portion having imperforate depending walls, a portion cooperating with one of said walls to form a downwardly disposed blow off muffler conduit, said conduit having an opening for connection with a blow off cock and an opening at the bottom for discharging the exhaust from said conduit, and baffle plates in said conduit disposed to break the force of steam passing therethrough.

2. As a new article of manufacture, an integral locomotive ashpan structure having depending side and end walls and including a hopper part and a blow off muffler part, and baffle elements in said muffler parts, the side walls of said parts being continuous and there being a reinforcing rib extending around said structure.

3. In a locomotive, an ashpan having side, front, and rear walls, and having a baffle plate for a blow off muffler integral with one of said walls.

4. As a new article of manufacture, a locomotive ash pan integral structure including a hopper, having imperforate depending walls, a partition adjacent one of said walls forming a blow off conduit therewith, and baffle plates within said conduit for breaking the direct passage of exhaust therethrough.

5. In a locomotive ashpan, an upper portion adapted to be secured to the firebox, and a lower portion comprising an integral hopper structure having imperforate depending walls, one of said walls being bifurcated to form opposite walls of a steam conduit having an inlet opening for connection with a blow off cock and an outlet opening at the bottom for discharging steam and water to the track and away from said structure.

6. In a locomotive ashpan structure, an upper part for attachment to the firebox and an integral hopper part having imperforate

side and end walls, one of said walls being offset outwardly from the corresponding wall of said upper part, a partition adjacent said offset wall forming an exhaust conduit therewith having an outlet opening at the bottom, and baffle elements in said conduit.

In testimony whereof I hereunto affix my signature this 5th day of May, 1931.

EDMOND I. HETSCH.
